2,305,227

ADVERTISING DISPLAY DEVICE

Walter Steinhilber, New York, N. Y., assignor to
 Brett Lithographing Company, Long Island
 City, N. Y.

Application September 18, 1941, Serial No. 411,296

6 Claims. (Cl. 40—4)

This invention relates to advertising display devices and more particularly to types used in connection with containers, such as bottles for beverages.

The main object of the invention is to provide an attractive, mantle-like, display card, shaped and adapted to engage around the upper part of a conventional bottle, and bear conspicuously, ornamental, preferably colored, configurations, together with advertising legends relating to the 10 contents of the container.

A further feature is to provide an advertising medium inexpensively produced from card board stock material, capable of bearing illustrations, in some way referring to the liquid in the container, that is suited prior to use, to be compactly stacked for storage and transportation, readily curved to suit a bottle when required, and provided with interengaging means whereby it may be retained when in adjusted position.

These advantageous purposes are accomplished by the novel and practical construction and combination of integral parts hereinafter described and illustrated in the accompanying drawing, constituting a component of this disclosure, and in which—

Figure 1 is a front elevational view of an embodiment of the invention, showing its application to a conventional bottle.

Figure 2 is a side elevational view of the same.

Figure 3 is a rear view thereof.

Figure 4 is a plan view of the device in its flat blank form, sheared and pierced ready for use.

Figure 5 is a top plan view of the device as disposed on a bottle.

As indicated, the device is cut from a sheet of card board, printed and embellished preferably in colors prior to cutting, the blank presenting a substantially circular main portion 15.

This disc-like element is represented being grasped, at its opposed marginal edges by connections, shown as hand depicting elements 16, integral with arms 17 extending from shoulders 18, centrally above which extends an upright neck 19.

This neck extends to a cheek element 20 adjoining a face 21 having on its opposite side edge another cheek element 22, partially separated by an enclosed, sinuous slot 23, a similar but reversed cut 24 intervening the face 21 and cheek 20, the lobe like elements attached to the face appearing, in the finished display, as curled locks of hair, see Figure 1.

The outer part of the cheek element 22 is sheared to produce an upright slot 25 having

angular ends and adapted to have inserted therein a tenon 26 formed on the outer edge of the cheek element 20 in such manner as to lockingly engage the end members in slightly conical, generally cylindrical formation.

The circular disc 15 is partially separated from the shoulder member 18 by a narrow crescent shaped cut 27 and presents a surface suited to bear advertising matter, as at 28.

The bottle shown consists, as usual, of a cylindrical body A blending into a conically contracted neck B, terminating in a mouth C, provided with a stopper D.

To apply the device, the elements 25 and 26 are connected forming an annulus to engage readily on the bottle top, obscuring the mouth C and stopper D; the neck 19, now at the rear and centrally of the device, is bent along the scored lines as shown in Figure 4 and the arms 17 twisted, 20 relative to the shoulders 18, in such manner that the display device disc 15, partially curved in conformity with body of the bottle, is disposed at an angle closely adjacent to the body, clearly presenting whatever legend it may bear to the attention of an observer.

While the device is described as being composed of card board, it is apparent that any other thin sheet material, as Celluloid or metal may be preferred and which may be used with equal facility.

From the foregoing, it will be seen that an attractive display device has been disclosed in its preferred embodiment, subject to such changes as may come within the scope of the appended claims.

Having thus described the invention and set forth the manner of its construction, application and use, what is claimed as new and sought to secure by Letters Patent is:

40. 1. An advertising device applicable to bottle shaped containers comprising, a unitary blank cut from sheet material and shaped to depict a human figure including a head, shoulders and arms terminating in hands, a disc bearing advertising matter connected by said hands, said disc separated at its upper edge from said shoulders to pass over a container neck to rest against the body thereof, said arms extending forwardly and downwardly at the sides, said head having lateral horizontal extensions, one of said extensions terminating in a tongue and the other extension slit to receive said tongue thereby to constitute a flexible band engageable over the container neck, said head obscuring the top of the container and said disc disposed therebelow over the

container body, all of said elements colored to represent a clothed human figure and constructed from a single piece of material.

2. An advertising device applicable to bottle shaped containers having a body, top and stopper comprising a unitary blank cut from sheet material and shaped to depict a human figure including a head, shoulders and arms terminating in hands, a disc bearing advertising matter integrally connected by said hands, said disc separated at its upper edge from said shoulders to pass over a bottle neck to rest against the bottle body, said arms extending forwardly and downwardly at the bottle sides, said head disposed against the uppermost part of the bottle above said disc obscuring the bottle stopper, lateral extensions on said head foldable to produce a band encircling the bottle top, and means combined with said band to unite the ends thereof, all of said elements of integral construction.

3. An advertising device applicable to bottle shaped containers comprising a unitary blank cut from sheet material and shaped to depict a human figure including a head, shoulders and arms terminating in hands, a disc bearing advertising matter connected by said hands, said disc separated at its upper edge by a crescent shaped cut from the shoulders and arms to permit passage of the upper portion of a container and attached by said hands to the arms, a strap-like element extending laterally from said head to encircle the container near its top, a tongue on the opposite side of said head, and a slot near the end of said strap-like extension receptive of said tongue.

4. An advertising display for bottles comprising a blank of sheet material having a face and side elements, interconnecting means at the outer extremities of said side elements to produce a tapered annulus fitting around the bottle top, a neck portion extending from one of said side elements, a shoulder connected thereto, said neck and shoulder being disposable at the rear of the bottle, arms at the ends of said shoulder extending to the front around the bottle sides, and a circular plate connected to said arms disposable on the front of the bottle and adapted to carry advertising matter, all parts being of integral construction.

5. An advertising display for bottles comprising a unitary sheet material blank, cut, shaped and colored to represent a human face having cheek portions, tenon and mortise connections at the outer ends of said portions engageable to form a conical band to engage around a bottle top, a transverse shoulder-like member connected to said portions to extend at the rear of the bottle, arms at the ends of said member to extend downwardly at the sides, and a legend carrying disc connected by said arms at the front of the bottle.

20 6. In an advertising display device for bottles, a sheet material blank shaped to produce a legend bearing disc disposed on one side of the bottle, an ornamental head thereabove, said head constituting a hollow annulus, means to secure said head around the bottle neck, and connections between said head and disc reaching around the sides of the bottle, all of said elements being of integral construction.
